UNITED STATES PATENT OFFICE

SAMUEL H. MARSH, OF WINSTON-SALEM, NORTH CAROLINA

APPARATUS FOR WASHING BOTTLES

Application filed December 8, 1927. Serial No. 238,562.

My invention consists in new and useful improvements in apparatus for washing and rinsing bottles, and has for its object to provide a device whereby the bottles in the process of being washed, will be subjected to the maximum fluid contact.

A further object of my invention is to provide apparatus of the above class, wherein a balanced high pressure fountain head arrangement is employed, thus enabling the bottles to be retained in the cups or containers by opposed pressure.

A still further object is to provide a bottle carrier chain capable of universal movement, whereby the cups may be conveyed around wheels arranged on any axis.

A further object of my invention is to provide means for eliminating the slack in the chain of cups.

With the above and other objects in view which will appear as the description proceeds, my invention consists in the novel features herein set forth, illustrated in the accompanying drawings, and more particularly

pointed out in the appended claims.

Referring to the drawings, in which numerals of like character designate similar parts throughout the several views,

Fig. 1 is an interior plan view of the apparatus, showing the course traveled by the bottle conveying chain, and the means for eliminating the slack in said chain.

Fig. 2 is a vertical sectional view of a fountain head and sprocket wheel, showing my improved balanced high pressure arrangement.

Fig. 3 is a plan view of one form of fountain head.

Fig. 4 is a plan view of a fountain head in the form of a quarter segment, and

Fig. 5 is an end view of the tank, partly broken away.

Fig. 6 is a front view of the exterior conveyor wheels, at right angles to Fig. 1, showing diagrammatically the course traveled by the bottle conveying chain after leaving the tank.

Figs. 7 and 8 are views in side elevation and plan, respectively, of a section of my im-

proved bottle conveying chain, showing the cups secured thereto.

In the drawings, 1 represents a suitable tank, U-shaped in cross section, as clearly shown in Fig. 5, and having a false bottom 2, located intermediate the upper and lower extremities of said tank. 3 designates an inlet opening at one end of the tank 1, for the incoming chain of bottles, and 4 represents a similar outlet opening at the other end of the tank, said openings 3 and 4 being adapted to serve as couplings when a plurality of tanks are to be used in communication with one another.

On the false bottom 2, I mount a plurality of horizontally disposed lower fountain heads 5, 6, 7, 8 and 9, as shown in Fig. 1, the heads 5, 6 and 8 being in the form of half segments of a circle, and the heads 7 and 9, in the form of quarter segments. These fountain heads are all in communication with a main pump discharge line 10, by means of suitable connections.

Each of the fountain heads above referred to consists of a main body portion provided with a circumferentially extending closed cavity 12, into which said line 10 discharges. The upper face of the body portion is provided with a series of apertures equipped with detachable spraying nozzles 13 which open into said cavity 12, whereby the fluid forced into said cavity from the pump line 10, is discharged into and onto the bottles to be cleaned, as hereinafter set forth. At a suitable point in each fountain head, I insert a cleaning or washout plug 14, which may be removed when it is desired to blow out or clean the fountain head.

15 represents a vertically disposed shaft mounted centrally of fountain heads 5 and 6, in sand proof bearings, and extending upwardly through the top 1^a of the tank, where it operatively engages a suitable gear driving arrangement 16, whereby said shaft is positively driven. At the lower end of each shaft 15, just above the fountain head, is a sprocket wheel 17, keyed to the shaft in any suitable manner and driven thereby, said wheel being provided on its periphery with a series of vertically extending grooves or

recesses 18, adapted to engage the bottle conveying cups, as hereinafter described.

The wheels 17^a are similar to the wheels 17, but are not power driven, being freely rotatable on short non-rotatable shafts 15^a, in the fountain heads 7, 8 and 9, by the chain of cups.

Secured to the top 1^a of the tank, immediately above the lower fountain heads just mentioned, but oppositely disposed with respect thereto, is a series of upper fountain heads 19, also in communication with the pump line 10, having downwardly projecting discharge nozzles 20, each directly in line with the adjacent nozzle 13 in the lower head, said upper heads being in all respects identical with the respective lower fountain heads.

21 represents an endless chain conveyor comprising a series of interlocked loops or links, alternately lying in planes at right angles to the adjacent links, as clearly shown in Figs. 7 and 8. To the outer side of each vertical link, and alternately arranged on opposite sides of said chain, I weld or otherwise 25 permanently secure bottle containers or cups 22, open at top and bottom, and adapted to receive the neck of an inverted bottle 23. The outer wall of each cup is provided with a horizontally disposed half circular lug 24, for engaging a circumferentially extending groove 30 located centrally of the periphery of the sprocket wheels 17 and 17^a, when the chain is in place, whereby said chain is prevented from rising off of said wheels as it travels on its 35 course through the tank 1.

When the chain of cups is in place, the cups 22 are vertical and engage the recesses 18 in the sprocket wheels, as they come in contact therewith, the positively driven wheels 17 40 moving in clock-wise direction, and causing the chain 21 to follow the course indicated by the arrows shown in Fig. 1.

In order to eliminate any slack in the chain 21, I mount the intermediate fountain head 45 8 on a pivot 25 on the head 7, by means of an arm or extension 26 at the adjacent end of the body portion of the fountain head 8, as shown in Fig. 1. This pivot 25 and arm 26 are provided with conduits in communication with 50 one another, and with the cavity 12 in each of the fountain heads 7 and 8, whereby fluid connection is made between the pump line 10 and head 8, through the medium of head 7.

At the opposite end of the head 8, I provide 55 an ear 27, to which is secured one end of a cable 28 which extends horizontally to the wall of the tank 1, where it passes under a pulley 29 at the edge of the false bottom 2. From this pulley 29, the cable passes upwardly 60 along the inner wall of the tank, and over another pulley 30, mounted on the top 1^a of the tank at the side edge thereof, and down along the outer wall of said tank. At the outer end of the cable 28, I provide an adjustable balance weight 31 of sufficient weight to

70 maintain a constant outward pull on the free end of the fountain head 8, to eliminate any slack in the chain of cups, it being understood that the movement of the fountain head is transmitted to the sprocket wheel through the shaft 15^a, fixed to the former.

Adjacent the outlet end of the tank 1, I 75 mount a vertical wheel 32, rotatable about a horizontal shaft 33, its upper extremity being in direct line with the outlet opening 4 in said tank. Beneath the plane of this wheel 32, and intermediate said wheel, and the tank 1, I provide a horizontally disposed wheel 34 rotatable around a vertical shaft 35, its lateral extremities lying within those of wheel 32, and a similar wheel 36 rotatably mounted adjacent said wheel 32 on the same shaft.

Upon emerging from the tank 1, through the outlet 4, the chain of cups passes over and under the wheel 32, around the wheel 34 on its side adjacent the tank, and then under and over the wheel 36 from whence it travels horizontally on the guide rails 37 back to the inlet opening 3 through the medium of a suitable sprocket wheel or wheels (not shown).

80 It is obvious, the apparatus exterior of the tank 1 may be enclosed in a suitable casing to prevent the escape of the fluid from the tank through the inlet or outlet openings.

85 38 represents an outlet in the bottom of the tank 1, in communication with a suction pump (not shown) by means of a conduit 39, and 40 designates a second conduit connected into the pressure side of said pump and leading therefrom directly into the feed line 10. It will thus be seen that the cleaning fluid falling by gravity to the bottom of the tank 1, will be sucked into the pump above referred to, through conduit 39, and then forced back under pressure through conduit 100 40 into the feed line 10 from whence it again passes through the various fountain heads.

105 Having thus described the construction of my improved apparatus, the operation is as follows:

110 The chain of cups is loaded with bottles at the inlet end of the tank in any desired manner, with the bottles inverted as shown in Fig. 2. The driving mechanism is set into motion, causing the sprocket wheels 17 to be positively driven in clockwise direction, and at the same time, the pump (not shown) is turned on to cause a constant flow of cleaning fluid under pressure, through the line 10, and into each of the lower fountain heads 5, 6, 7, 8, and 9, and the upper fountain heads 19.

115 Any desired cleaning fluid may be employed, but I have found by experience, that the most effective compound is a mixture of sand, water and caustic soda, which, when applied under pressure, will thoroughly cleanse the most polluted bottles.

120 As the wheels 17 rotate, they cause the chain of bottles to travel around each of the fountain heads, following the course indi-

cated by the arrows in Fig. 1, each bottle registering intermittently with each corresponding nozzle in each fountain head as it passes thereover.

5 It will be seen from Fig. 2 that at the same time, the solid stream of fluid is playing on the inside of the bottle from each lower fountain head, a solid stream under equal pressure is being played on the bottom of the inverted bottle from the corresponding upper fountain head, thereby not only balancing the pressure applied to the inside of the bottle to retain said bottle in the cup, but also cleaning the outside of said bottle.

10

15 After passing over the last fountain head 9, the chain of bottles emerges from the tank through the outlet 4, and passes over the vertically disposed wheel 32, where the bottles are unloaded in any desired manner. The
20 chain of empty cups then passes under the wheel 32, around the horizontal wheel 34, and under and over the wheel 36, from whence it travels along the rails 37, back to the inlet end of the tank for reloading.

25 It may be stated that in most instances, a rinsing tank is employed between the cleaning tank and unloading wheel 32, but as this tank is practically a duplicate of the one just described, it is believed unnecessary to more
30 than mention the same.

From the foregoing, it is believed that my invention may be clearly understood by those skilled in the art without further description, it being borne in mind that numerous changes may be made in the details of construction without departing from the spirit of the invention as set forth in the appended claims.

What I claim and desire to secure by Letters Patent is:

1. Apparatus for washing bottles, including a tank, a series of horizontally disposed non-rotatable fountain heads mounted in said tank, each having a plurality of nozzles and supporting a sprocket wheel rotatable thereon, an endless chain of bottle conveying cups extending through said tank passing around each of said sprocket wheels and in line with the spraying nozzles of each of said fountain heads, and means for positively driving certain of said sprocket wheels to cause said chain to travel through said tank.

2. Apparatus for washing bottles, including a tank having inlet and outlet openings, a series of horizontally disposed non-rotatable fountain heads mounted in said tank, each having a plurality of nozzles and supporting a sprocket wheel rotatable thereon, an endless chain of bottle conveying cups passing into said tank at the inlet opening, around each of said sprocket wheels in line with the nozzles of each of said fountain heads, and out through the outlet opening, means for conveying said chain back to the said inlet opening, means for positively driv-

ing certain of said sprocket wheels, and means for eliminating the slack in said chain.

3. Apparatus as claimed in claim 2, wherein the means for eliminating slack consists in pivotally mounting one of said fountain heads at one end, the opposite end having a cable secured thereto, said cable passing over a series of pulleys and having a weight secured to the free end thereof.

4. In a bottle washing machine, a series of upwardly discharging fountain heads, a series of downwardly discharging fountain heads directly above said first named series, each fountain head being in line with the respective head in the opposite series, a sprocket wheel rotatably mounted adjacent the upper face of each of said upwardly discharging fountain heads, and an endless chain of bottle conveying cups adapted to pass around said sprocket wheels, each of said heads being in communication with a common pressure pump line, whereby solid streams of cleaning fluid under equal pressure are played on the bottles in said cups in opposite directions, the downwardly discharging heads balancing the pressure of the upwardly discharging heads to retain the bottles in said cups.

5. Apparatus for washing bottles, comprising a tank having a top and a false bottom, a series of upwardly discharging fountain heads secured to said false bottom, a series of downwardly discharging fountain heads secured to the under side of said top, each upper head being in direct alignment with the opposed lower head, a shaft extending from each lower head to the respective upper head, at least one of said shafts being positively rotatable, and having a sprocket wheel keyed thereto immediately above the lower head, each of said other shafts having sprocket wheels rotatably mounted thereon immediately above their respective lower heads, an endless chain of bottle conveying cups passing around each of said sprocket wheels, and between the opposed upper and lower heads, all of said heads being in communication with a common source of fluid under pressure, and means for rotating said positively rotatable shaft. 105 110 115

6. In apparatus for washing bottles, a fountain head comprising a body portion having a circumferentially extending closed cavity, a series of discharge nozzles in the upper face of said body in communication with said cavity, a cleaning aperture in one wall of said body opening into said cavity, a closure for said aperture, and a sprocket wheel mounted on and rotatable with respect to the upper face of said body for conveying a chain of bottles around said fountain head 120 125

7. Apparatus as claimed in claim 5, where-
in said tank is U-shaped in cross section and
provided in its bottom with a discharge out-
let, and means for conveying the cleaning 130

fluid collected in the bottom of said tank, back to its source.

8. Apparatus as claimed in claim 2, where-
in the means for conveying the chain back to
the inlet opening in said tank comprises a
vertically rotatable wheel adjacent the out-
let opening, a horizontally rotatable wheel
beneath the plane of said first named wheel
and between it and said tank, a second ver-
tical wheel in line with said first named wheel,
10 and a guide rail in line with said second ver-
tical wheel, extending along side of said tank,
back to the inlet end thereof, said chain pass-
ing from the outlet opening over and under
said first vertical wheel, around said hori-
zontal wheel, under and over said second ver-
tical wheel, onto said guide rail, and back to
the inlet opening.

In testimony whereof I affix my signature.
SAMUEL H. MARSH.
